COMBINED BUMPER, GRILLE, AND LAMP UNIT FOR AN AUTOMOBILE

Clifford C. Voss, Clawson, Mich., assignor to Chrysler Corporation, Highland Park, Mich., a corporation of Delaware

Application July 29, 1957, Serial No. 47,124

Term of patent 7 years

(Cl. D14—18)

FIG. 1

FIG. 2

FIG. 3

FIG. 4

Fig. 1 is a front elevational view of a combined bumper, grille, and lamp unit for an automobile showing my new design;

Fig. 2 is a top plan view thereof;

Fig. 3 is a side elevational view thereof; and

Fig. 4 is a section taken on the line 4-4 of Fig. 1. I claim:

The ornamental design for a combined bumper, grille, and lamp unit for an automobile, substantially as shown.
